CONTROL SYSTEM

Robert S. Elberty, Jr., Wilkinsburg, Pa., assignor,
by mesne assignments, to The American Laundry Machinery Company, a corporation of Ohio

Application August 13, 1931, Serial No. 556,819

15 Claims. (Cl. 34—5)

My invention relates generally to control systems and particularly to control systems for drying machines, such as drying tumblers for laundries and the like.

- 5 As is apparent, the efficiency and capacity of a drying machine may be materially increased by providing a control system that functions to discontinue the drying process when the moisture of the material is reduced to a predetermined value. 10 In this manner, the material is not kept in the drying machine for any longer period of time than is necessary.

In this connection, it has been determined by tests that the electrical conductivity of cloth varies from substantially zero, when dry, to a relatively high value at 50% of moisture saturation and above. To utilize this change in conductivity for control purposes is an object of my invention.

20 It is also an object of my invention to provide a control system of the class indicated that shall be simple and reliable and be readily and economically manufactured and installed.

Another object of my invention is to provide 25 for extracting moisture from damp material and for discontinuing such extracting process when the moisture content of the material is reduced to a predetermined value.

A further object of my invention is to provide 30 for controlling the operations of a drying machine in accordance with the moisture content of the material being dried.

A more specific object of my invention is to provide for discontinuing the operations of a drying 35 machine when the electrical conductivity of the material attains a predetermined value.

Other objects of my invention will hereinafter 40 become apparent.

For a fuller understanding of the nature and 45 the objects of the invention, reference should be had to the following detailed description taken in connection with the accompanying drawing, in which:

Figure 1 is a diagrammatic view of a control 50 system constructed in accordance with my invention and shown in relation to a drying tumbler, and

Fig. 2 is a view, in vertical cross-section, taken along the line II—II of Fig. 1 and showing particularly a door-operated switch and the manner in which the current conducting bars are disposed within the rotatively-mounted receptacle.

Referring now to the drawing, reference character 10 represents an enclosure or housing for 55 a drying machine, such as a drying tumbler for

laundries and the like. A cylinder 12 having perforations 14 is rotatively mounted within the housing and constitutes a receptacle in which the material to be dried is disposed during the drying process.

As illustrated, a motor 20 of any suitable type is provided to rotate the cylinder 12 by means of gear wheels 22 and 24. As is the usual practice in drying machines, a current of hot air is passed through the cylinder 12 and brought into intimate contact with the material in order to reduce the drying time to a minimum. For this purpose, a fan 16 mounted on top of the housing 10 is provided. A motor 17 of any suitable type, preferably one that may operate in parallel with the motor 20, is provided to rotate the fan 16 during the drying process. The motors 17 and 20 are simultaneously energized from a source of three-phase power comprising the supply conductors 45, 46 and 47 when the switch 70 is energized.

A cold cathode gaseous electric discharge device 35 of a familiar type that is disposed to be influenced by the moisture content of the material being dried, is connected in circuit with the relay 60. When the moisture content of the material being dried is above a predetermined amount, the electric discharge device 35 operates a relay 60, which, in turn, establishes a circuit for closing the switch 70. Conversely, when the moisture content of the material being dried is reduced to a predetermined amount by the drying process, the electric discharge device 35 ceases to operate, thereby deenergizing the motors 17 and 20.

During the drying process, the motor 17 operates the fan 16 to induce a draft of heated air through the cylinder 12 in order to hasten the drying process. The air upon entering the housing 10 through an opening 19 provided in the bottom part thereof passes over the heating elements 18, such as steam pipes.

Also during the drying process, the motor 20 slowly rotates the cylinder 12 in order to provide for uniformly drying the material and also for lessening the drying period. As is the usual practice, a plurality of inwardly projecting longitudinal ribs 26, as illustrated, are disposed within the cylinder to stir or to agitate the material as the cylinder rotates.

However, in the preferred embodiment of my invention, I provide for constructing each rib of a current-conducting bar 28 insulated from the periphery of the cylinder by means of an insulating bar 26 of Micarta or any other suitable in-

sulating material. In this manner, the ribs may be utilized as part of the control circuit as well as means for stirring the material while the cylinder rotates.

5 Preferably, as shown, the conducting bars 28 are connected at one end by means of a ring 30 which in turn is electrically connected to the control electrode 36 of the electric discharge device 35, by means of a slip ring 32, insulated from the cylinder, and conductors 37 and 38.

10 The anode 40 and the cathode 41, which will be referred to as the principal electrodes of the electric discharge device are connected across one phase of the three-phase supply source. This

15 circuit extends from the supply conductor 45 through conductors 49 and 50, the principal electrodes 40 and 41, conductor 51, a manually-operated switch 52, conductor 53, the contact members of the door-operated switch 61 (see Fig. 2), 20 conductor 54, the magnetizing windings of relay 60, and conductor 55 to the supply conductor 46.

25 The principal electrode 40 is also connected in circuit with the cylinder 12 by means of a slip ring 43 that is electrically connected to the cylinder, and a conductor 44.

Consequently, the voltage between the control electrode 36 and the principal electrode 40 varies in accordance with the electrical conductivity of the material that is connecting the bars 30 28 to the cylinder 12. If the conductivity is high, as it will be when the material is very damp, the voltage between the control electrode 36 and the principal electrode 40 will likewise be high. At the same time, since the voltage between the principal electrodes 40 and 41 is substantially constant and equal to the voltage across the supply conductors, the voltage between the control electrode 36 and the principal electrode 41 increases. Therefore, when the voltage between the control electrode 36 and the principal electrode 40 decreases to a predetermined value, as determined by the moisture content of the material, the voltage between the control electrode 36 and the principal electrode 41 correspondingly increases to a predetermined value and causes the electric discharge device to operate.

50 The operation of the electric discharge device 35 permits current to flow freely between the principal electrodes 40 and 41 and thereby energizes the relay 60. Accordingly, the closing of the contact members of the relay 60 establishes a circuit for energizing the magnetizing winding of switch 70. In this manner the motors 17 and 55 20 are energized from the supply source through the closing of the contact members of the switch 70. At the same time that the switch 70 is closed, a potential is established across a visible signal 75, such as a lamp. This is to indicate 60 to the attendant that the motors are energized.

As hereinbefore explained, when the electric-discharge device 35 is operating, the motor 17 drives the fan 16 for inducing a draft of heated air through the cylinder 12 for hastening the 65 drying process. Likewise, the motor 20 rotates the cylinder in which the clothes are disposed in order to produce a churning action to provide uniform drying. The motors continue to operate until the drying process has reduced the 70 electrical conductivity of the material to a predetermined value, or in other words, until the moisture content of the material is reduced to a predetermined value.

75 As the moisture content of the material gradually decreases, the voltage between the control

electrode 36 and the principal electrode 40 gradually increases and, correspondingly, the voltage between the control electrode and the principal electrode 41 gradually decreases. When the voltage between the control electrode 36 and the principal electrode 41 decreases to a predetermined value, the electric discharge device ceases operating, thereby deenergizing the relay 60 and the motors 17 and 20. The opening of the switch 70 likewise deenergizes the signal 75, which indicates to the attendant that the drying process has ceased.

An adjustable impedance device 76, which may be a resistor, a capacitor, or a reactor, or a combination of these, but which is preferably a resistor, is connected across the control electrode 36 and the principal electrode 41. As is apparent, the voltage between the control electrode and principal electrode may be varied by changing the value of the impedance of the device 76. Therefore, by varying the effect of the impedance device 76, the electric discharge device 35 may be caused to operate in accordance with any predetermined value of the moisture content of the material being dried.

25 Although I have preferably shown a cold cathode gaseous electric discharge device in the embodiment of my invention because of its desirable operating characteristics, I do not limit myself to such device, since other electric discharge devices, such, for example, as a grid controlled mercury vapor tube, a vacuum tube, or a hot cathode gaseous electric discharge device may be utilized.

30 In the interest of safety and also as a matter of convenience for the attendant, a door-operated switch 61 is provided to disrupt the control circuit through actuating coil of relay 60 when the door 11 is open (see Fig. 2). As is apparent, upon the opening of the door, the illustrated spring biases the contact members to open-circuit position.

35 I have thus shown and described a control system that provides for controlling the operations of a drying machine in accordance with the moisture content of the material being dried.

40 Since certain changes may be made in the above-described construction and since different embodiments of my invention may be made without departing from the spirit and scope thereof, it is intended that all matter contained in the foregoing description or shown in the accompanying drawing shall be interpreted as illustrative and not in a limiting sense.

45 I claim as my invention:

50 1. A machine for drying material comprising, in combination, means for extracting moisture from said material, an electric discharge device disposed to be affected by the moisture content of said material, and means responsive to the condition of the electric discharge device for discontinuing the action of said extracting means.

55 2. A machine for drying material comprising, in combination, means including means for producing a draft of air for extracting moisture from said material, an electric discharge device disposed to be affected by the moisture content of said material, and means responsive to the condition of the electric discharge device for discontinuing the action of said extracting means.

60 3. A machine for drying material comprising, in combination, a receptacle for containing said material, means for establishing a draft of air to said material for drying said material, an electric discharge device disposed to be affected

by the moisture content of said material, and means responsive to the condition of said electric discharge device for controlling the operation of said draft-establishing means.

4. A machine for drying material comprising in combination, a receptacle for containing said material, a fan, an electric motor for driving said fan to establish a draft of air to said material for drying said material, an electric discharge device disposed to be affected by the moisture content of said material, and means responsive to the condition of said electric discharge device for controlling said motor.

5. In a machine for drying material the combination of a receptacle for containing said material, current-conducting means insulated from the receptacle and disposed to make contact with said material, an electric discharge device, a source of electrical energy and means including said receptacle and said current-conducting means for connecting said electric discharge device in circuit with said source of electrical energy.

6. A machine for drying material comprising, in combination, containing means for said material, current-conducting means insulated from said containing means and disposed to make contact with said material, means for establishing a draft of air in contact with said material, an electric discharge device connected in circuit with said containing means and said current-conducting means and disposed to be influenced by the moisture content of said material, and means responsive to the condition of the electric discharge device for controlling the draft-establishing means.

7. A machine for drying material comprising, in combination, a rotatively mounted receptacle for containing said material, means for rotating the receptacle, current-conducting means insulated from said receptacle and disposed to make contact with said material, a fan for establishing a draft of air, means for driving said fan, an electric discharge device connected in circuit with said receptacle and said current-conducting means and disposed to be influenced by the moisture content of said material, and means responsive to the condition of said electric discharge device for controlling said means for rotating said receptacle and said means for driving said fan.

8. A machine for drying material comprising, in combination, a rotatively mounted receptacle for containing said material, a motor for rotating said receptacle, current-conducting means insulated from said receptacle and disposed to make contact with said material, a motor-driven fan for establishing a draft of air, means for energizing said motors, an electric discharge device connected in circuit with said receptacle and said current-conducting means and disposed to be influenced by the moisture content of said material, and means responsive to the condition of said electric discharge device for deenergizing the motors.

9. A machine for drying material comprising, in combination, a receptacle for containing said material, means for operating said receptacle, means for establishing a draft of air to said material for drying said material, an electric discharge device disposed to be affected by the moisture content of said material, and means responsive to the operating condition of said electric discharge device for controlling the opera-

tions of said means for operating the receptacle and said draft establishing means, respectively.

10. A machine for drying material, in combination, a receptacle for containing said material, receptacle operating means, a fan, an electric motor for driving said fan to establish a draft of air to said material for drying said material, an electric discharge device connected to be affected by the moisture content of said material, and means responsive to the condition of said electric discharge device for controlling the receptacle operating means and the said motor, respectively.

11. In a machine for drying material, moisture extracting means for drying said material, means for passing a current of electricity through said material, and means actuated when the flow of said current through said material is reduced below a predetermined value due to increase in resistance of said material to the flow of said current because of the extraction of moisture therefrom to discontinue the action of said moisture extracting means.

12. A machine for treating material comprising, in combination, means for supporting the material to be treated, means for extracting moisture from said material, electrical means arranged in circuit with said material so as to be affected by moisture content of said material, and means responsive to the condition of said electrical means for discontinuing action of said extracting means.

13. A machine for treating material containing moisture and having different electrical characteristics with different moisture contents, in combination, means for producing a draft of gaseous fluid for extracting moisture from said material, means for heating the gaseous fluid, means for passing an electric current through said material, and means actuated when the flow of said current through said material is varied a predetermined value due to the change in electrical characteristics of the material by reason of the change in moisture content, to discontinue the action of said means for producing a draft of gaseous fluid.

14. A machine for drying material comprising, in combination, a support for the material, current-conducting means insulated from said support and including means adapted to make contact with said material, means for establishing a draft of gaseous fluid in contact with said material to extract moisture therefrom, electrical means connected in circuit relation with said support and said current-conducting means and thus adapted to be influenced by the moisture content of the said material, and means responsive to the electrical condition of said electrical means for controlling the draft-establishing means.

15. A machine for drying material comprising, in combination, a rotatively mounted container for the material, means for rotating the container, current-conducting means insulated from said receptacle and adapted to make contact with said material, a fan for producing a draft of gaseous fluid to the material, means for driving the fan, electrical means interconnected with the container and the current-conducting means and adapted to be influenced by the moisture content of said material, and means, responsive to the condition of said electrical means, adapted to control the means for rotating said container and for driving said fan.
